US0D1013519S

(12) **United States Design Patent** (10) **Patent No.:** **US D1,013,519 S**
(45) **Date of Patent:** **** Feb. 6, 2024**

(54) **BOTTLE**

(71) Applicant: **SHENZHEN STARISE CREATION TECHNOLOGY CO., LTD**, Shenzhen (CN)

(72) Inventor: **Shaofeng Li**, Shenzhen (CN)

(73) Assignee: **SHENZHEN STARISE CREATION TECHNOLOGY CO., LTD**, Shenzhen (CN)

(**) Term: **15 Years**

(21) Appl. No.: **29/909,078**

(22) Filed: **Aug. 1, 2023**

(30) **Foreign Application Priority Data**

Jul. 14, 2023 (CN) 202330441977.7

(51) **LOC (14) Cl.** **09-01**

(52) **U.S. Cl.**

USPC **D9/536**; D9/549

(58) **Field of Classification Search**

USPC D9/499, 516, 520, 528, 530, 531, 549,

D9/535, 534, 533, 536; D7/509, 510,

D7/533, 536

CPC B65D 1/265; A47G 19/2266; A47J 41/02;

A45F 3/16

See application file for complete search history.

Primary Examiner — Darcey E Gottschalk

(57) **CLAIM**

The ornamental design for a bottle, as shown and described.

DESCRIPTION

FIG. 1 is a perspective view of a bottle showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of portion 9 shown in FIG. 2; and,

FIG. 10 is an enlarged view of portion 10 shown in FIG. 3.

The dash-dash broken lines in the drawings depict portions of the bottle that form no part of the claimed design. The dot-dash broken lines represent boundaries of the enlarged portions and form no part of the claimed design.

1 Claim, 10 Drawing Sheets
